UNITED STATES PATENT OFFICE

1,925,103

INSULATING BUILDING BLOCK

Donald A. Leftus, Cleveland, Ohio, and Andre M. Mertzanoff, New York, N. Y.

Application May 28, 1930. Serial No. 456,668

5 Claims. (Cl. 72—41)

Our invention relates to improvements in building structures, and has for its object to provide a building block or wall member which is simple in construction, easy to produce, and efficient in use.

Further, said invention has for its object to provide a building block or wall member formed of plastic material, and having incorporated therein means for insulating certain of its wall portions or sides from other thereof.

Further, said invention has for its object to provide a building block or wall member formed of plastic material having incorporated therein one or more layers of insulating material for preventing the exchange or transfer of heat from one side or portion thereof to another side or portion thereof.

Further, said invention has for its object to provide an interlocking or interengaging building block or wall member formed as an integral structure of plastic material having incorporated therein one or more layers or sections of insulating material for preventing the exchange or transfer of heat from one portion or side to another portion or side thereof.

Further, said invention has for its object to provide a building block or wall member formed as an integral structure of plastic material having incorporated therein, upon or adjacent to certain of its opposite sides or wall portions relatively thin sheets or layers of insulating material serving to prevent the exchange or transfer of heat from one of said sides or wall portions to the other thereof, and serving also to maintain the portion of the block intermediate said insulated portion at a substantially uniform or neutral temperature.

Other objects will in part be obvious and in part be pointed out hereinafter.

To the attainment of the aforesaid objects and ends, my invention consists in the novel features of construction and in the combination, connection and arrangement of parts, hereinafter more fully described and then pointed out in the claims.

In the accompanying drawings, showing illustrative embodiments of the invention—

Figure 1 is a perspective showing one form of single block constructed according to, and embodying our said invention;

Fig. 2 is a perspective view illustrating another shape of block;

Fig. 3 is a front view, partly broken away and in section showing a portion of a wall constructed of blocks of the form illustrated at Fig. 2;

Fig. 4 is a front elevation partly broken away and in section illustrating a modification;

Fig. 5 is a longitudinal section on the line 5—5 of Fig. 4.

Fig. 6 is a transverse, vertical section illustrating a further modification, and

Fig. 7 is a central section showing a mold and the manner of forming a block therein.

In said drawings, referring to Figs. 1 and 2, 10 designates a wall member or building block formed as an integral unit of molded plastic material, such as cement, concrete molded to shape and dried, or it may consist of terra cotta or refractory material, and be formed either as a solid or

70 as hollow cellular block.

The member or block may be made in any desired shape or size, but is herein shown a rectangular body portion 11 formed, for example, of concrete having openings 12, 12 extending vertically therethrough separated by an integral 75 partition 13. The term "vertically" as herein used refers to the contemplated portion of the block when built into a wall. The opposite major sides are provided at their vertical edges with raised marginal portion or ribs 14, 14 having their 80 inwardly facing edges undercut at 15, 15 to receive and retain a layer of heat-insulating material 16 such as asbestos, whose center surface is substantially flush with the outer surfaces of 85 the marginal portions 14, 14. One outer or vertical side of the block 10 is provided with a layer of plastic material which constitutes the exposed surface or facing 17 of the block which is designed for exposure when the block is in use. In

the present instance the outer side of said facing 17 is made to simulate a plurality of bricks 18, such as are commonly employed in building structures, and suitably scored by lines 19 to imitate the cement or mortar whereby bricks are secured in 90 position to form a wall. It will, of course, be 95 obvious, and it is intended that the facing 17 may be formed of any suitable plastic material, and of any color so as to simulate brick, stone, cement stucco, or other material, and that the 100 same may be plain, smooth surface or be ornamented in alto or bas relief as desired.

In the modification illustrated at Figs. 2 and 3 the wall member or block 10^a is formed as a pyramid unit simulating the appearance of a wall section composed of six bricks 18^a having their 105 joints or seams 19^a broken in the usual manner. This form of block possesses the advantage that alternate blocks may be reversed, as shown by broken lines, and thus produce the appearance of 110 an ordinary brick wall. The unit, except for its

shape, is formed in the same manner as above described in connection with Fig. 1 and comprises the central or body portion 11^a, vertical openings 12^a, adapted to register with registering similar openings in contiguous blocks; insulating layer 16^a, anchoring ribs 14^a, and facing portion 17^a.

At Figs. 4 and 5 the wall member or block 10^b is constructed substantially like that shown at Fig. 1, except that in this instance body portion 11^b is preformed and provided in its front face with a plurality of under-cut or dovetail recesses 12^b, to receive anchoring members 13^b; 13^b formed integrally with the facing 17^b and extending through the heat-insulating layer 16^b, in order that the several parts may be more firmly secured together. Where desired or necessary the inner or rear face of the block may be formed with similar anchoring means for its facing.

In the modification illustrated at Fig. 6, the block 10^c has its central or body portion 11^c formed of cement or other suitable material, as hereinabove described, and has its outer facing 20 on its outer surface which is composed of a mixture of plastic material and heat-insulating material, such as asbestos integrally molded with the body portion 11^c. The inner or rear surface of the block in the present construction is formed entirely by an insulating block 16^c of asbestos or the like.

In producing a wall member or block according to our invention, we take a mold, have the inner side of its base shaped to produce the exterior surface of the unit, and first pour into the mold a quantity of plastic material to constitute the facing 17. While the facing material is still plastic we next place into the mold a slab or layer of insulating material 16 which is slightly shorter than the length of the block and has its shorter edges bevelled as shown. Hereupon the plastic material constituting the body of the block is poured into the mold to within a short distance of the top thereof, and the inner slab or layer of insulating material 16 placed thereon whereupon the final plastic layer 17 constituting the inner side of the block is poured into the mold, and the entire mass then subjected to pressure, and caused to dry or harden.

It is to be noted that by means of our invention, we are enabled to provide a building block or unit which will reduce to a minimum the exchange or transfer of heat. Thus by reason of the slabs or layers of insulation arranged at, or near the inner and outer sides of the block, the interior of a building will be protected and insulated against the transfer of cold from without, and at the same time the transfer of heat from the interior of the building to the outside

will be prevented. The central part of the block between the insulating slabs or layers will therefore at all times possess a uniform or neutral temperature.

Further, it is to be noted that by reason of our improved construction, and the insulating properties, a higher and more uniform temperature may be maintained within the building at a much lower expenditure of fuel than would be possible in ordinary building construction.

It will also be obvious that any number of slabs or layers may be employed, and that the same may be disposed centrally of the block, or at or adjacent to one or more of its wall portions.

Having thus described our said invention, what we claim and desire to secure by Letters Patent is.

1. A wall member formed as an integral unit comprising a block of molded material, a vertical layer of insulating material incorporated into the same along one vertical face thereof, and a finishing facing disposed over said layer of insulating material, substantially as specified. 95

2. A wall member formed as an integral unit 100 comprising a block of molded plastic material, a layer of insulating material incorporated into the same along one vertical face thereof, and a facing of plastic material covering said layer of insulating material, substantially as specified.

3. A wall member composed of molded plastic material formed as an integral unit of pyramidal form with stepped sides, and insulating material incorporated into the same adjacent to certain of its sides, a portion of said plastic material 110 serving to cover said insulating material, and constituting the facing of said wall member, substantially as specified. 105

4. A wall member composed of molded plastic material formed as an integral unit of pyramidal 115 form with stepped sides, and having vertical openings extending therethrough, and insulating material incorporated into the same adjacent to certain of its sides, a portion of said plastic material serving to cover said insulating material, and constituting the facing of said wall member, substantially as specified. 120

5. A wall member comprising a block of molded material, a relatively thin layer of insulating material incorporated into the same upon at 125 least one of its vertical wall portions, and finishing facing disposed upon and united with said layer of insulating material, substantially as specified.
